TOOTH HOLDER

Filed June 17, 1922

By

E. W. Bond

Attorney

Inventor
George R. DeNise

UNITED STATES PATENT OFFICE.

GEORGE R. DE NISE, OF ROCHESTER, MINNESOTA.

TOOTH HOLDER.

Application filed June 17, 1922. Serial No. 569,068.

To all whom it may concern:

Be it known that I, GEORGE R. DE NISE, a citizen of the United States, residing at Rochester, in the county of Olmsted and 5 State of Minnesota, have invented certain new and useful Improvements in Tooth Holders, of which the following is a specification.

This invention relates to certain new and 10 useful improvements in means for mounting or holding in place artificial teeth or plates in position within the mouth and it has for its object among others to provide a simple and efficient device for this purpose that will 15 effectually hold the plate in position when the mouth is wide open, and which will readily accommodate itself to any movement of the jaws, and without discomfort to the wearer.

20 The device is capable of manufacture at small cost, readily applied, not liable to displacement or injury, and dispenses with the necessity of the usual expensive and unsightly bridgework generally resorted to.

25 Other objects and advantages of the invention will hereinafter appear and the novel features thereof will be particularly pointed out in the appended claims.

The present invention is capable of embodiment in a variety of forms, some of the 30 most preferable of which are herein disclosed.

The invention, in such preferred forms, is clearly illustrated in the accompanying 35 drawing, which, with the numerals of reference marked thereon, form a part of this specification, and in which—

Figure 1 is an elevation showing the application of one form of holder.

40 Figure 2 is a plan view of a set of teeth of the lower jaw.

Figure 3 is a perspective view of another form of holder.

45 Figure 4 is a perspective view of still another form.

Figure 5 shows a similar view of another form.

Figure 6 is a like view of still another form.

50 Figure 7 is an end view, and Figure 8 is a plan view of still another form.

Figure 9 is a perspective view of a further modification, and

Figure 10 shows in perspective still another form. 55

Like numerals of reference indicate like parts throughout the different views.

Referring to the drawings, 1 designates an upper plate and 2 a lower 60 plate carrying the teeth 3 and 4, respectively.

My improved holder consists broadly of an elliptical spring which is designed to be disposed between the plate and the cheek of 65 the wearer. This I have found from actual experience to be the only practical thing for the purpose. Numerous forms of springs may be employed, but all serve in the same way. In the form shown in Figures 1, 2 and 70 3 will be seen a holder 5 of arcuate form, the bowed part 6 of which terminates at each end in an annular enlargement 7 in the form of an open ring. In applying such a holder, the portions 7 are adapted to be disposed between the plates and the cheeks of the wearer, the bowed portion conforming to the curvature of the plate, one strand 8 conforming to and cooperating with the front portion of 75 the upper plate, and the lower strand 9 likewise conforming to and cooperating with the front portion of the lower plate. The holder is formed of spring material, preferably wire, and may be fastened in any suitable manner. 80

For instance, the method of fastening the 85 wire which goes inside or outside of the teeth may be simply by means of small staples— 10, which pass through the plate on about the line where the teeth meet the rubber gums, the staples being clinched on the opposite 90 side of the gums, and filed smooth, of course; in other words, the false plate is bored along the said line to take the staple which clinched with the wire spring inside of it. No matter what type of plate is used the spring 95 should be stapled in about two places as shown in Figure 2.

The holder shown in Figure 4 has the arcuate portion 11 with the bowed upper strand 12 and the lower strand 13, the bowed 100 portion terminating in the ring or circular portions 14, lateral offset portions being provided at the ends of the bowed portion, as seen at 15 and 16.

The form shown in Figure 6 is to all intents and purposes substantially the same as that shown in Figure 4, but having a single arcuate or bowed portion 17, with

ring or annular portions 18 at the ends, there being also lateral offsets 19 joining the ends of the bow with the portions 20 extending inwardly from the rings 18, the ends of the wire being free and the rings open, to give greater resiliency.

In the form shown in Figure 5, the holder has the bow-shaped portion 21, which is in the form of an open ring having the offset portions 22.

The forms shown in Figures 5 and 6 are adapted for use on a single plate, either upper or lower.

In Figures 7 and 8 the holder embodies the arcuate or bowed portion 23 with upper and lower strands 24 and 25 inclined toward each other and merging into circular or annular portions 26 comprising each a plurality of coils.

In the form shown in Figure 9 the holder is formed with the arcuate or bowed portion 27 having the upper strand 28 and the lower strand 29, but instead of having annular or ring-like portions at the ends the wire is bent upon itself, as shown at 30, which portions are designed to engage the cheeks of the wearer.

Figure 10 shows still another form which has the arcuate portion composed of the upper and lower strands 31 and 32, respectively, said strands being convergent and joined at their ends by the small spring coils 33. This form is practically the reverse of that shown in Figures 7 and 8.

In all of the forms shown the mode of application to the teeth or plates is substantially the same, and arcuate portion or portions may be stapled or otherwise secured to the plate or plates.

Modifications in detail may be resorted to without departing from the spirit of the invention or sacrificing any of its advantages.

In the form shown in Figure 4 the front strand or arcuate portion is to be run inside the teeth instead of outside.

The form shown in Figure 6 is for use in connection with one plate only, either upper or lower, instead of two. This form is for an upper or lower plate of one or more teeth per plate at the corner of the mouth, at about the location of the eye-teeth, and for one side of the mouth only.

The form shown in Figure 5 is for the

purpose of holding an upper and lower plate on either side of the jaw in the neighborhood of the eye-teeth.

What is claimed as new is:—

1. A holder for teeth for the purpose set forth embodying a member with resilient end portions and a resilient arcuate portion continuous of said end portions and adapted to extend around the front and to opposite sides of the jaw.

2. A holder for teeth for the purpose set forth embodying an arcuate portion with resilient end members adapted to engage the cheeks of the wearer upon opposite sides of the jaw, said arcuate portion being continuous and uninterrupted from one end member to the other.

3. A holder for teeth for the purpose set forth embodying an arcuate portion with resilient end members adapted to engage the cheeks of the wearer upon opposite sides of the jaw, said arcuate portion being continuous and uninterrupted from one end member to the other, said end portions being of enlarged area.

4. A holder for teeth for the purpose set forth embodying an arcuate portion with resilient end members adapted to engage the cheeks of the wearer upon opposite sides of the jaw, said arcuate portion being continuous and uninterrupted from one end member to the other, said arcuate portion having upper and lower strands.

5. A holder for teeth for the purpose set forth embodying an arcuate portion with resilient end members adapted to engage the cheeks of the wearer upon opposite sides of the jaw, said arcuate portion being continuous and uninterrupted from one end member to the other, said arcuate portion having upper and lower strands, and said end portions having convolutes.

6. A holder for teeth for the purpose set forth embodying an arcuate portion with resilient end members adapted to engage the cheeks of the wearer upon opposite sides of the jaw, said arcuate portion being continuous and uninterrupted from one end member to the other, said end members being enlarged vertically to extend above and below the upper and lower teeth.

In testimony whereof I affix my signature,

GEORGE R. DE NISE.
